UNITED STATES PATENT OFFICE

92,020

DESIGN FOR A PORTABLE CABINET OR SIMILAR ARTICLE

Harry Rodstein and Isidore Nathanson, Brooklyn, N. Y.

Application February 12, 1934, Serial No. 50,704

Term of patent 7 years

To all whom it may concern:

Be it known that HARRY RODSTEIN and ISIDORE NATHANSON, are both citizens of the United States, and residents of Brooklyn, in the county of Kings and State of New York, have invented a new, original, and ornamental Design for Portable Cabinets or Similar Articles, of which the following is a specification, reference being had to the accompanying drawing, forming part thereof, in which, Figure 1 is a perspective view of the rear side of the portable cabinet or similar article, and Figure 2 is a perspective view of the front side thereof showing our new design.

We claim:

The ornamental design for a portable cabinet or similar article as shown.

Dated, February 7, 1934.

HARRY RODSTEIN.
ISIDORE NATHANSON.
